DOUBLE ACTION SPRAYER

Filed Aug. 27, 1928

UNITED STATES PATENT OFFICE

ESEK O. CORSON, OF BERKELEY, CALIFORNIA

DOUBLE-ACTION SPRAYER

Application filed August 27, 1928. Serial No. 302,193.

The invention forming the subject matter of this application relates to double action pumps, especially adapted to be used in connection with sprayers.

5 The primary object of the invention is the provision of a double action pump for attachment to any container having an opening thereon adapted to receive the pump, and the pump being especially adapted to be 10 used in connection with drums generally employed for transferring chemicals such as insecticides for the purpose of destroying weeds or insects.

In particular, the object of the invention 15 is the provision of a double action pump for the purpose of accomplishing a continuous spray of chemicals, forced from a container, by the reciprocation of the plunger of said pump therein to a spray nozzle or the like.

20 Another object of the invention is the provision of a double action pump which may be readily inserted into a container and which is adapted to transfer fluid from the container into the pump casing or cylinder at the upward stroke of the plunger, and to deliver approximately half of the fluid from said cylinder at the downward stroke of the plunger and to deliver the other half of the fluid from said cylinder at the upward stroke of 25 the plunger, at the same time pumping another charge of fluid from the container into said cylinder.

Other objects of the invention are to provide a device of the character described that 35 will be superior in point of simplicity, inexpensiveness of construction, positiveness of operation, and facility and convenience in use, and general efficiency.

In this specification, and the annexed 40 drawing, the invention is illustrated in the form considered to be the best, but it is to be understood that the invention is not limited to such form because it may be embodied in other forms, and it is also to be understood 45 that in and by the claims following the description, it is desired to cover the invention in whatsoever form it may be embodied.

In the drawing—

50 Figure 1 is a vertical sectional view of the pump as attached to a container, showing a

spray nozzle connected to the outlet opening of the pump;

Figure 2 is an enlarged sectional view of the lower end of the pump, showing the arrangement of the valve in the end of the cylinder and of the inner valve in the end of the plunger; and

Figure 3 is a top plan view of the pump and the container to which the pump is attached.

Referring to the accompanying drawings, wherein similar reference characters designate similar parts throughout, the pump in its entirety is denoted by the numeral 6, and a container is designated by the numeral 7. In the top of the container 7 is an opening 8 into which is fixedly secured a reinforcing bushing 9, the aperture of said bushing being provided with an internal thread. A vent 11 is also provided in the top of the container for the purpose of admitting atmospheric air pressure into the tank.

60 The pump 6 comprises a casing 12 having a handle portion 13 thereon. The lower end of the casing 12 terminates in a stem 14 provided with external threads for engagement with the internal threads of the bushing 9. A flange 16 determines the threading of the end 14 into the bushing 9.

65 A cylinder 17 is fixedly secured into the lower end of the stem 14, as at 18. The lower end of the cylinder is provided with internal threads, as at 19, into which is secured a valve body 21, an aperture 22 of which is controlled by a ball check valve 23. A pin 24 is transversely disposed across the valve opening above the ball 23 so as to prevent the accidental removal of the ball. It is to be noted 70 that extensions may be secured into the lower end of the cylinder and the check valve may be secured into the free end of the last extension, thereby assuring a proper length for the pump so that the same reaches to the bottom of a container.

75 A plunger 26 is reciprocable in the cylinder 17 and is slidably supported in the casing 12. At the upper end of the casing 12 is a packing box 27 of any suitable construction so as to prevent the escapement of fluids from the casing 12. An outlet opening 28 on the cas- 80

ing 12 is disposed below the packing box 27. The handle 13 is made hollow so as to provide an air chamber thereat. A passage 29 is formed inside of the casing 12 in continuation of the chamber of the cylinder 17. The air chamber inside of the handle 13 and the outlet opening 28 communicate with the passage 29 around the outside circumference of the plunger 26. A handle 31 is secured to the upper end of the plunger 26. The plunger 26 is tubular, and the upper end thereof is properly sealed by means of a plug 32. The lower end of the tubular plunger 26 terminates in an inner valve denoted in its entirety by the numeral 33, a valve body 24 of which is firmly secured into the internally threaded lower end of the plunger 26.

The valve body has an annular flange 36 thereon for tightly securing a pair of leather cups 37 against the end of the plunger 26. The leather cups 37 have an inside diameter substantially corresponding to the outside diameter of the tubular plunger 26 and the outside diameter thereof is slidably in the chamber of the cylinder 17. When the valve body 34 is tightly screwed into the threaded end of the plunger 26, the leather cups 37 are securely and tightly held in place thereby. In the valve body 34 is disposed an inner ball 38 for controlling the aperture of the valve in the usual manner.

Above the valve body 34 are passages 39 connecting the passage of the tubular plunger 26 with the inside chamber of the cylinder 17. The portion of the tubular plunger containing the valve 33 and the passages 39 is separated from the rest of the inner chamber of the plunger by means of a suitable plug 41 fixedly secured inside of the tube above the passages 39. A plurality of apertures 42 is cut thru the walls of the tubular plunger 26 above the plug 41 for the purpose to be hereinafter described.

The outlet opening 28 of the casing 12 is internally threaded and is adapted to receive a tube 43 having a spray nozzle 44 attached to the free end thereof. It is to be noted that any suitable conduit, flexible or rigid, leading to any suitable nozzle, may be secured into the threaded opening 28.

The invention operates as follows: The pump is inserted into the bushing 9 so that the lower end of the pump is adjacent to the bottom of the container 7. The pump 6 and the container 7 are now held by the handle 13 in one hand, while the other hand operates the plunger 26 by exerting the required pull on the handle 31.

The first stroke of the plunger 26 is an upward stroke. The plunger is pulled upwardly until the leather cup 37 abuts against the casing 12 at about the lower edge of the outlet opening 28. It is to be noted that the hole thru the casing 12 is reduced at the upper end above the passage 46 connecting the cham-

ber of the handle 13 with the passage 29. During the upward stroke of the plunger 26 the suction created in the chamber 17 draws the ball 23 inwardly, thereby permitting the passage of fluid thru the aperture 22. Thus the action of the plunger pumps the fluid from the container 7 into the cylinder 17. It is to be noted that the capacity of the cylinder 17 is approximately twice the volume of the portion of the plunger 2 extended into the cylinder 17 at the end of its downward stroke. Thus, when the handle 31 is pressed downwardly, and the plunger 26 is moved thereby, the pressure exerted on the fluid in the cylinder 17 will firmly close the check valve 23, and at the same time will cause the opening of the check valve 33. Now, during the downward stroke of the plunger 26, the fluid, having no other outlet, will flow into the lower part of the tubular plunger 26 and thru the apertures 39 into the concentric space between the plunger 26 and the cylinder 17. As it was heretofore stated, when the plunger 26 is at the end of its down stroke, it occupies one-half of the total capacity of the cylinder 17 and the casing passage 29, so that when the fluid is forced into the concentric space outside of the plunger, there is only sufficient space to hold one-half of the volume of the fluid forced thru the valve 33 by the downward stroke of the plunger 26. Therefore, the other half of the fluid forced thru said check valve will be delivered under pressure thru the outlet opening 28 thru the tube 43 and nozzle 44, thereby spraying the fluid thru said nozzle. The chamber of the handle 13 and the chamber provided above the opening 42 inside of the tubular plunger 26 function as the air chambers of the double acting pump, so as to still further assist in effecting a continuous flow thru the outlet opening 28 thru the nozzle 44.

During the next upward stroke of the plunger 26, the pressure of the fluid closes the valve 33, and the leather cup 37 forces the remaining fluid from the concentric space between the plunger 26 and the cylinder 17 out thru the outlet opening 28. At the same time, the suction created by the upward stroke of the piston 26 will draw in another charge of fluid from the container 7 into the cylinder 17 in the manner heretofore described.

It will be recognized that a continuous flow is readily effected by the use of the pump heretofore described because while a full charge is drawn into the cylinder 17 at every upward stroke of the piston 26, at the same time, the remaining half of the fluid around the plunger is delivered thru the nozzle 44; and during the next downward stroke of the piston 26, while the whole content of the cylinder 17 is forced thru the valve 33, one-half of this fluid is immediately forced out thru the outlet opening 28 and nozzle 44, the other half remaining in the concentric space

around the plunger 26 and being delivered from the pump during the next upward stroke of the piston 26.

It will also be recognized that the pump 5 may be secured in containers of any size by providing the respective container with an opening adapted to receive the threaded portion of the casing 12, or by providing bushings or nipples on the threaded portion of the 10 casing 12 so as to make the same fit any larger openings in the top of a container. Also extensions may be provided at the lower end of the cylinder 17 in the manner heretofore described, so that the valve 21 reaches close to 15 the bottom of the container. The length of the plunger 26 is such that the same extends above the packing 27 at the end of its downward stroke. In order to repair or clean the inner valve, it is only necessary to remove the 20 lower valve body 21 from the cylinder 17. Then by advancing the plunger 26 to the full length thereof thru the cylinder 17, the inner valve 33 protrudes outside of the lower end of the cylinder 17, thereby allowing the re- 25 pair or the cleaning thereof.

From the foregoing, it is thought that the construction, use, and many advantages of the herein-described sprayer pump will be adequately understood. It will be further understood that certain material alterations in the construction may be effected without having a deleterious effect on the efficiency of my device. The minor details in the construction will at all times, of course, be performed 35 within the scope and spirit of the subjoined claims.

I claim:

1. A sprayer comprising a container having an air inlet vent therein, a centrally bored 40 nipple in screw-threaded engagement with one end of the container and extending to the approximate bottom thereof, a tubular plunger having apertures through its walls and concentric within the nipple, the nipple 45 being closed at its outer end and provided with a valve in its lower end, the plunger being closed at its outer end and provided with a valve at its lower end, a plug within the plunger and intermediate the apertures 50 through the wall of the plunger, a hollow handle formed on the nipple in communication with said nipple and spaced from the container, a sprayer and communicating means between the sprayer and the interior 55 of the nipple.

2. A sprayer comprising a container having an air inlet vent therein, a centrally bored nipple in screw-threaded engagement with one end of the container and extending to the 60 approximate bottom thereof, a tubular plunger having apertures therein through its walls and being placed concentric within the nipple, a plug within the hollow tubular plunger, the said hollow tubular plunger ex- 65 tending above said plug, the nipple being

closed at its outer end and provided with a valve at its lower end, the plunger being closed at its outer end and provided with a valve at its lower end, the apertures through the wall of the plunger being intermediate 70 the valve and the plug, a sprayer, and communicating means between the sprayer and the interior of the nipple.

In testimony whereof I affix my signature.

ESEK O. CORSON.
